UNITED STATES PATENT OFFICE.

EDMOND A. FORDYCE, OF BOSTON, MASSACHUSETTS, ASSIGNOR TO THE LAMSON COMPANY, OF NEWARK, NEW JERSEY, A CORPORATION OF NEW JERSEY.

PNEUMATIC-DESPATCH-TUBE APPARATUS.

1,076,969.

Specification of Letters Patent.

Patented Oct. 28, 1913.

Application filed April 23, 1906, Serial No. 318,134. Renewed March 13, 1908. Serial No. 420,804.

To all whom it may concern:

Be it known that I, EDMOND A. FORDYCE, of Boston, in the county of Suffolk and State of Massachusetts, have invented certain new and useful Improvements in Pneumatic-Despatch-Tube Apparatus, of which the following is a specification.

My invention relates to improvements in power control for pneumatic despatch tube apparatus and its object is to maintain a vacuum in the transit tubes only during the period of transmission of a carrier through said tubes; also to insure the positive delivery of a carrier at its destination in extremely long lines without increasing the size of the piston and cylinder controlling mechanism.

In the accompanying drawings which illustrate a construction embodying my invention, Figure 1 is a side elevation of the apparatus showing the several controlling connections. Fig. 2 is a cross sectional view of the transit tube and switch showing the trip projecting into said tube in the path of the carriers. Fig. 3 is a side elevation of Fig. 2. Fig. 4 is a top view showing the inlet valve in connection with the switch. Fig. 5 is a side elevation of Fig. 4. Fig. 6 is a side elevation of the suction drum and controlling mechanism in section.

Like letters of reference refer to like parts throughout the several views.

The transit tube A for the transmission of carriers has at one end a bell-mouth opening A' to receive carriers. The opposite end of said transit tube A is connected with the upward discharge terminal A³ having a valve A⁴ closing the despatch opening and of the usual construction in the art. Connected with said terminal A³ is a transit tube B for returning carriers; this tube B is provided at its upper end with a carrier-inlet opening closed by the pivoted valve B' of usual construction. The lower or discharge end of said transit tube B is closed by the ordinary type of valve B². Connected with the lower end of said tube by the joint B³ is a suction tube C the lower end of which connects with the upper chamber D' of the casing D (see Fig. 6). The lower chamber D² of said casing D is in communication by means of the pipe E' with the suction drum E. The valve F, connected with the piston G by the stem G' and operated by said piston, controls communica-

tion between said chambers D' and D². The cylinder H located in the lower part of said casing D, and in which said piston G operates, communicates with the lower chamber D² by the port H' and at the opposite end is a passage H³ normally closed to the atmosphere by the valve J. Connecting said passage H³ with the lower chamber D² is a smaller passage H⁴ controlled and graduated by the needle valve K and held in position by the check nut K'.

Mounted upon an extension of the casing D and in position to operate the valve J is the magnet L; from the magnet L extend the wires M and M' through which wires, when the circuit is closed by one of the switches along the system, the battery N will energize the magnet L and cause the operation hereinafter described.

Mounted at suitable intervals along the transit tubes A and B are switches P (Figs. 1 and 2). The switches P consist of the casing P' encircling the transit tube and carrying pivoted therein the shaft P² to which shaft is attached the finger or trip P³ projecting into the transit tube. On the opposite end of the shaft P² is mounted the fiber disk P⁴ fixed thereon by the pin P⁵. The contacts P⁶ are mounted on the inner face of said disk P⁴ and are fastened to metal strip P⁷ by screws P⁸. These contacts P⁶ are adapted upon oscillation of the shaft P² to contact with the metal spring strips P⁹ which are separated by insulating disk P¹⁰ and connected with wires S^a S^b. The spring P¹¹ is adapted to hold the switch in open or normal position as shown in Fig. 3. A similar switch R' is operated by the inlet valve B' (Figs. 4 and 5). In place of a trip the valve door is pinned to the shaft P² and the opening of the valve closes the circuit. The switch R is connected at the bell-mouth opening A' with the main wires M M' by the wires S S'. The switch R' at the inlet B' is connected directly with the main wires M M'.

The operation is as follows: If a carrier is to be despatched from the central station to a substation, the carrier is inserted into the bell mouth opening A' (Fig. 1); the carrier striking the trip in said bell mouth opening operates the switch R thereby closing the circuit and energizing the magnet L. This causes the valve J to be drawn back opening the passage H³ to the atmosphere.

The air entering through said passage destroys the vacuum beneath the piston G thereby forcing said piston upward as the vacuum is maintained through the port H'; this operation will cause the valve F to open so that air is drawn from the atmosphere at the bell mouth A' through the chamber D', thence through the chamber D² and suction tube E' into the suction drum E. The carrier is drawn into the tube A and upon passing the trip at the switch R said trip resumes its normal position thereby breaking the circuit with the magnet L, releasing the valve J and closing the passage H³ to the atmosphere. The air beneath the piston G is gradually drawn through the passage H⁴ and valve K into the chamber D²,—the piston G gradually dropping of its own weight until the pressure on both sides of the piston is equalized and the valve F closes. If the transit tube A is extremely long this closing of the valve F may take place before the carrier has delivered, in which event the said carrier will operate the trips P³ of the switches P thereby closing the circuit and energizing the magnet L, causing the operation to be repeated until the carrier is discharged through the valve A⁴ at the terminal A³. If it is desired to return a carrier to a central station, the valve B' is opened and the carrier inserted into the tube B. The opening of the valve B' closes the circuit and energizing the magnet L causes the operation as hereinbefore described. The valve is now closed, the circuit broken, and the carrier drawn through the transit tube B discharges through the valve B² on to the receiving shelf B⁴. In the meantime, the operating of the switches P in said tube B insures the delivery of the carrier by successively re-timing the mechanism which controls communication between the transit tube and the air-exhausting means.

Having thus described the nature of my invention and set forth a construction embodying the same, what I claim as new and desire to secure by Letters Patent of the United States is:

1. In a pneumatic despatch tube system, a transit tube for the transmission of carriers, an air-exhaust pipe communicating with the transit tube, a normally closed valve controlling the communication between the air-exhaust pipe and the transit tube, electrically actuated means for moving the valve to open the communication between the air-exhaust pipe and the transit tube, a source of electricity, an electric circuit extending along the transit tube and including the source of electricity and the electrically actuated means for moving the valve, a series of normally open switches interposed in the electric circuit, and a series of carrier-actuated mechanisms projecting

into the path of travel of the carriers through the transit tube with each of said mechanisms connected with a switch in the electric circuit so that a carrier passing through the tube and operating through said mechanisms will successively close said switches to energize at intervals the electrically actuated means to open the valve controlling the communication between the air exhaust pipe and the transit tube. 75

2. In pneumatic despatch tube systems, a transit tube for the transmission of carriers, an air-exhaust pipe communicating with the transit tube, a casing interposed in the communication between the air-exhaust pipe and the transit tube, an apertured partition dividing the casing into two communicating chambers with one chamber communicating with the transit pipe and the other chamber communicating with the air-exhaust pipe, a cylinder provided with a port at its upper end communicating with the chamber in communication with the air-exhaust pipe and said cylinder having at its lower end a port leading to the outside air 90 and said cylinder also provided with a passage leading from its lower end to the chamber communicating with the air-exhaust pipe, a valve normally closing the port at the lower end of the cylinder, a valve normally closing the aperture in the partition between the chamber in the casing, a piston in the cylinder connected with the valve controlling the aperture in the partition, an electric magnet when energized operating 100 to open the valve controlling the port at the lower end of the cylinder to admit air to the cylinder to raise the piston to open the valve controlling the aperture in the partition to establish communication between the two chambers, an electric circuit including the magnet extending along the transit tube, a source of electricity in said circuit, a normally open switch in said circuit, and carrier-actuated mechanism projecting into the path of travel of the carriers through the transit tube so that a passing carrier operating through said mechanism will close the switch to energize the electric magnet. 110

3. In pneumatic despatch tube systems, a transit tube for the transmission of carriers, an air-exhaust pipe communicating with the transit tube, a casing interposed in the communication between the air-exhaust pipe 120 and the transit tube, an apertured partition dividing the casing into two communicating chambers with one chamber communicating with the transit pipe and the other chamber communicating with the air-exhaust pipe, a cylinder provided with a port at its upper end communicating with the chamber in communication with the air-exhaust pipe and said cylinder having at its lower end a port leading to the outside air and said 125

cylinder also provided with a passage leading from its lower end to the chamber communicating with the air-exhaust pipe, a valve normally closing the port at the lower end of the cylinder, a valve normally closing the aperture in the partition between the chamber in the casing, a piston in the cylinder connected with the valve controlling the aperture in the partition, an electric magnet 10 when energized operating to open the valve controlling the port at the lower end of the cylinder to admit air to the cylinder to raise the piston to open the valve controlling the aperture in the partition to establish communication between the two chambers, an electric circuit including the magnet extending along the transit tube, a source of electricity in said circuit, a series of normally open switches interposed in the electric circuit, and a series of carrier-actuated mechanisms projecting into the path of travel of the carriers through the transit tube with each of said mechanisms connected with a switch in the electric circuit so 20 that a passing carrier operating through said mechanisms will successively close the switches to energize the magnet at intervals during the passage of the carrier.

4. In a pneumatic despatch tube system, 30 the combination of a transit tube, air exhausting means connected with said transit tube for effecting the transmission of carriers

through the latter, mechanism normally operative to allow a carrier transmitting flow of air through said tube for a substantially determined interval of time and to automatically limit such flow of air to said time, after being initially actuated, and means actuated by a carrier in transit for re-timing said mechanism.

5. In a pneumatic despatch tube system, the combination of a transit tube, air exhausting means connected with said transit tube for effecting the transmission of carriers through the latter, mechanism normally operative to allow a carrier transmitting flow of air through said tube for a substantially determined interval of time and to automatically limit such flow of air to said time, after being initially actuated, and means actuated by a carrier in transit for re-timing said mechanism, said system having provisions for continuously admitting a substantially equable flow of air into said tube behind said carrier while the latter is in transit.

In testimony whereof, I have signed my name to this specification in the presence of two subscribing witnesses, this thirteenth day of April, A. D. 1906.

EDMOND A. FORDYCE.
